CLAIM

The ornamental design for a bracket for suspending a filter in front of a video monitor screen, as shown and described.

DESCRIPTION

FIG. 1 is a top perspective view of a bracket for suspending a filter in front of a video monitor screen showing my new design;

FIG. 2 is a bottom perspective view thereof;

FIG. 3 is a top plan view thereof;

FIG. 4 is a right side elevational view thereof, the left side elevational view being a mirror image.
